UNITED STATES PATENT OFFICE.

JOSEPH DURAND, OF NEW YORK, N. Y.

IMPROVEMENT IN BUTTONS.

Specification forming part of Letters Patent No. **142,686**, dated September 9, 1873; application filed November 11, 1872.

To all whom it may concern:

Be it known that I, JOSEPH DURAND, recently of Paris, France, now residing in the city and State of New York, have invented an Improvement in Buttons, of which the following is a specification:

Buttons have been made with a shank having a neck, and spring-catches have been used for confining the shank to the back plate or head, and a plate has been made with an opening sufficient to receive the head, and a slot at one side into which the neck of the shank is passed.

My invention consists in a spring-plate having a recess, into which the head of the round shank is received, in combination with such shank having a neck, and a plate with a slot that is enlarged at one end for the head of the shank to be passed through. Thereby the plate and the shank will be connected by slipping the shank along in the slot so that its head will be received into the recess in the spring. The reverse movement will separate the parts, the head in its movement pressing back the spring.

In the drawing, Figure 1 is an elevation of the said button applied to the plate of a cravat. Fig. 2 is a section, showing the spring and its recess. These parts are in larger size than usual, for greater clearness; and Fig. 3 is a section of the button and head in a form adapted to shirt-studs, &c.

The button-head *a* is of any desired character. The shank *b* is made with a collar at 2, to retain the shank in the button-hole when

the plate or head of the button is removed. The shank *b* is also made with a neck, 3, leaving a head, 4, at the end of the shank. The plate *d* is shown in Fig. 1 as upon or part of the cravat-frame, and in Fig. 3 it forms part of the ornamental head, said head or plate being of any suitable character, according to the use to which it is to be put. In the plate *d* is an elongated opening, that is large enough at one end for the head 4 to pass through freely, and the other end of the slot is of a size to grasp the neck 3 as it is slipped along therein. The spring *i* is attached to the plate *d*, and has a recess adapted to receive the head 4 of the shank *b*, when said shank is slipped to the narrow end of the slot. Thereby the shank will be retained in position by the ridge or projection 6, upon the spring, and when the shank is to be disconnected from the plate *d*, said shank is moved along in the slot with sufficient force to cause the head 4 to press back the spring *i* as the head passes over the incline 6.

I claim as my invention—

The spring *i*, with the ridge 6 and recess for the head 4, in combination with the shank *b*, with its neck 3 and head 4, and the plate *d*, slotted for passing such head 4 and securing the shank, as set forth.

Signed by me this 8th day of November, 1872.

J. DURAND.
